LAWRENCE C. GERLINGER, OF SEATTLE, WASHINGTON.

VALVE.

Application filed May 25, 1927. Serial No. 194,186.

This invention relates to improvements in gas venting devices for use in connection with casks, barrels, and the like, wherein it is desired to automatically vent accumulated 5 gases within the container without permitting the introduction of air.

The primary object of the present invention is the provision of a vent of this character which automatically operates under a 10 predetermined pressure from within the container to permit the escape of contained gases, the vent serving under all normal conditions to prevent the admission of air to the container.

15 The invention is illustrated in the accompanying drawings, in which:

Figure 1 is a sectional view illustrating the improved vent.

Figure 2 is a plan of the same.

20 Figure 3 is a plan of the tube with the spring removed to show the relation of the valve.

The improved vent comprises the usual bung or stopper 1 adapted for removable 25 insertion in the usual bung opening 2 of the container 3. This bung or stopper may be of any material or size, it being of course understood that if the cask is designed to contain acids or the like, the stopper will be 30 of a material which will not be affected by such acid.

A tube 4 is removably inserted in the bung or stopper, as by threading or the like, the bottom of the tube having an opening 5 registering with an opening 6 in and extending through the bottom of the bung or stopper. The bottom of the tube on each side of the opening 5 is provided with projections 7 preferably though not necessarily 40 rectangular, and a disk valve 8 freely slideable within the tube is formed with openings 9 to more or less loosely cooperate with the projections 7.

At a point above the valve, the tube 4 is 45 provided with radially projecting diametrically opposed arms 10 forming an upper limit for a disk head 11 on the upper end of a spring 12 coiled within the tube and bearing at its lower end upon the disk valve 8.

Obviously, the tension of the spring will 50 serve to hold the valve closed, thereby sealing the outlet 6 from the container, but upon generation of gases within the container to any degree for which the spring may be set, the pressure of such gases will overcome the 55 tension of the spring and force the valve upwardly to permit the gases to escape through the openings 9 in the valve around the projections 7.

It is intended that the valve shall afford 60 a gas escape opening through the openings 9 around the projections and hence the valve will not leave the projections in operation. The position of the valve is thus assured 65 under all conditions.

A plug 13 is arranged for threaded co-operation with the interior of the tube, such thread having a conical terminal 14 which, when the plug is seated, will exert additional pressure upon the spring to insure the sealing 70 of the valve under even abnormal pressures. This plug also operates to close the upper end of the tube 4, so that the possibility of accidental admission of air under any jarring conditions to which the container 75 may be subjected will be prevented.

What I claim to be new is:

The combination with a cask, having a bung hole, of a stopper for the bung hole, said stopper having a central chamber and a 80 central aperture in the bottom of the chamber, a tube fitting in the chamber, said tube having a bottom formed with an opening which registers with the aperture in the stopper, the bottom of the tube surrounding 85 the opening therein forming a valve seat, spaced guide lugs formed on said seat on opposite sides of the central opening, a valve having apertures to fit over the lugs on the valve seat, said apertures being larger than 90 the lugs to form exit openings when the valve is in open position, lugs projecting from the inner walls of the tube, a tension spring between the last mentioned lugs and the valve, and a removable plug for the tube. 95

In testimony whereof I affix my signature.

LAWRENCE C. GERLINGER.
